CLAIM

The ornamental design for a hat, as shown and described.

DESCRIPTION

FIG. 1 is a top and side perspective view of a hat, a zipper on the hat being closed;

FIG. 2 is a bottom and side perspective view thereof;

FIG. 3 is a first side elevation view thereof, the opposite side being a mirror image thereof;

FIG. 4 is a top plan view thereof;

FIG. 5 is a bottom plan view thereof;

FIG. 6 is a front elevation view thereof;

FIG. 7 is a rear elevation view thereof; and,

FIG. 8 is a top and side perspective view thereof with an opened zipper.

The strap fastener of the hat illustrated in broken depict portions of the hat that form no part of the claimed design.
